CHARLES W. MANN, OF LOS ANGELES, CALIFORNIA, AND ALEXANDER GORDON GALLOWAY, OF WASHINGTON, DISTRICT OF COLUMBIA.

PROCESS FOR THE COOLING OF FRUITS AND VEGETABLES IN REFRIGERATOR CARS.

Application filed July 5, 1928. Serial No. 290,647.

(GRANTED UNDER THE ACT OF MARCH 3, 1883, AS AMENDED APRIL 30, 1928; 370 O. G. 757.)

This application is made under the act approved April 30, 1928, and the invention herein described, if patented, may be manufactured and used by or for the Government 5 for governmental purposes without payment to us of any royalty thereon.

The natural air circulation in a refrigerator car with ice in the bunkers is into the top 10 bunker opening down through the bunker and out at the lower bunker opening into the body of the car. The circulation being set up by cooling the air in passing through the ice, the cold air being denser and heavier than the warm air in the car body. The cold air 15 then comes in contact with the lower layers of the lading in the car with the result that the produce in this lower layer is cooled more rapidly than that in the upper layer and with the result that the warmer upper layers of 20 produce sometimes deteriorate in shipments under ordinary standard refrigeration. The process of cooling which we have devised comprises the reversal of the direction of the movement of the air in the car by means of 25 electrically operated blowers placed in the bunkers of the refrigerator car so that the air passes in at the bottom bunker opening up through and around the ice and is forced out the top bunker opening on top of the 30 load of produce.

The drawing consists of one figure and shows a side sectional view of a portion of a railroad car with the refrigerating apparatus installed.

Referring to the drawing it will be seen that A represents a blower or exhaust fan positioned in the ice bunker B, which is completely filled with ice except for the space occupied by the blower. The portable fan 35 A rests on portable support H. In operation the blower forces the air out of the upper bunker opening C into the body of the car E, the opening C is covered with paper, canvas or some such material except for a small space opposite the delivery opening of the blower so that recirculation of the air around in any space at the top of the bunker is prevented. The operation of the blower in forc-

ing air out into the body of the car creates a partial vacuum in the ice bunker and air is 50 therefore drawn into the ice bunker at the lower bunker opening F and passes up through the ice, being cooled in passing, until it reaches the blower A where it is again forced out into the car body over the load. 55 The forcing out of this cold air onto the top of the load of produce cools the top layer more rapidly than is possible with loads under ordinary standard refrigeration. The cold air being heavier than the warm air 60 tends to pass down through the open crates or containers until it reaches the space underneath the floor racks from where it is drawn into the lower bunker opening of the ice bunker. The top of the load is thus 65 cooled rapidly and it is possible for example to reduce the average temperature of a car-load of strawberries 4° or more per hour and cool it down from 65° to a good carrying temperature of 40° in about six hours or 70 less, the rate of cooling and time being dependent on the type of blowers used.

It is designed to cool the cars of produce at the shipping point immediately after loading and before they are shipped. After cooling the blowers are removed from the bunkers of the cars and the natural circulation of air as described in the first part of this specification is set up and the lower layer of produce in 75 the car thoroughly cooled in transit. Various types of blowers or fans may be used. We have found a small type of centrifugal blower which delivers 400 or more cubic feet 80 of air per minute convenient and effective in this work. We do not wish to limit our claims 85 to a particular fan or blower as any type that has sufficient power to reverse the natural circulation of the air and produce a current of air up through the ice and force it out over the load of produce will cool the lading in 90 the upper layers more rapidly than it would be cooled under normal circulation in a refrigerator car under standard refrigeration.

We claim:

A process of cooling products stacked in a 95 refrigerator car having an ice bunker, which

consists in initially causing air by forced circulation to flow upwardly through the ice in the bunker, thus cooling the air, spreading said cold air over the top of the stacked products from whence it sinks down through the products, thereby cooling them and thence back again to the bunker to be again circu-

lated, continuing the circulation until the proper low temperature has been reached; then discontinuing the forced circulation and then further cooling the products by natural circulation of air in the reverse direction. 10
